UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

BUCKET FOR TURBINES.

No. 863,118.

Specification of Letters Patent.

Patented Aug. 13, 1907.

Application filed February 14, 1906. Serial No. 301,027.

To all whom it may concern:

Be it known that I, GEORGE E. STEVENS, a citizen of the United States, residing at Lynn, in the county of Essex and State of Massachusetts, have invented certain new and useful Improvements in Buckets for Elastic-Fluid Turbines, of which the following is a specification.

The present invention relates to buckets for elastic-fluid turbines and has for its object to provide a form of bucket which is simple in construction and cheap to manufacture.

In the accompanying drawings, which illustrate one of the embodiments of my invention, Figure 1 is a partial axial section of a turbine of the Curtis type; Fig. 2 is a partial detailed view showing the buckets in place on the wheel or other support; Fig. 3 a view of one of the punchings; and Fig. 4 is an enlarged detail view of a slight modification.

1 represents the main shaft of the turbine and mounted thereon is the wheel 2 having as many peripheral projections 3 as there are rows of buckets. Between each two projections is a groove or depression in which is located the bucket securing means. When two or more rows of wheel buckets are provided, intermediate buckets 4 are provided which are mounted on supports 5, the latter being carried by the wheel casing 6. Elastic fluid is admitted to the buckets by the nozzle or other fluid discharging device 7. This nozzle may be of the expanding or non-expanding type, as desired, and preferably but not necessarily it is of the sectionalized type. The energy of the motive fluid is transformed into work in successive operations and is finally discharged into the exhaust chamber 8, the latter being connected with the condenser or any suitable exhaust.

35 In the present illustration, three rows of wheel buckets are shown, and for that reason my description will be directed chiefly to the wheel construction having that number of rows of buckets, but it is to be understood that the number can be increased or decreased, as desired. The buckets 9 are punched out of sheet metal and are formed integral with the base 10. In practice the buckets and the base are stamped out of sheet metal in one operation; by a second operation the buckets are bent at right angles, or substantially right angles, to the base; the next step is to form or shape the portions 11 that are situated between the projections 3 on the wheel or other support when the parts are assembled. Located in the groove between the projections 3 are retaining devices 12, made in the form of segmental rings 50 and secured to the wheel by screws 13. The rings are made in segments of suitable length and the plane of division between the sections or segments may co-incide with one of the retaining screws 13, as shown in the right-

hand side of Fig. 2, or the plane of division may be located midway between said screws, as shown in the 55 left-hand side of Fig. 2.

In order to secure the outer end of the base portions 14 of the buckets, the wheel is dove-tailed, or in other words, each side is provided with an overhanging wall 18 that engages with and retains the beveled end of the 60 part 14. Since there is more or less spring to the connecting portion 10 and the bases 14, the three buckets can be inserted by simply bending or buckling the portions 10 and 14, these portions afterward being straightened out by the locking rings and retaining screws 13. 65 If desired, however, the stock forming the wheel can be rolled or forced over the bases 14, as shown in Fig. 4. In other words the edge portion of the wheel or support is deformed at 18 and is afterwards cured of its deformity by forcing the part 18 over the base 14 to secure the 70 buckets. I may, however, use the locking rings with a different form of base securing means.

Each row of buckets is provided with a cover 15 made of sheet metal and provided with a series of openings arranged in a row to receive the tenons 17 formed on 75 the ends of the buckets. The cover is secured in place by riveting over the tenons on the buckets. The plane of division between the segments may be located midway between the segments, as shown in the left-hand side of Fig. 2, or it may coincide with the tenon, as 80 shown in the right-hand side of Fig. 2.

I have shown the invention in connection with the wheel buckets only, since they are much more numerous than the intermediate buckets and the expense of making them is, therefore, considerably greater. It is 85 to be understood, however, that the invention is also applicable to the intermediate buckets.

The invention is shown in connection with a machine of the impulse type, but it is to be understood that it can be used with a reaction or other type of machine. 90

It is evident from the foregoing that as many buckets may be stamped in one operation as are desired, with suitable connecting portions 10. The invention is particularly applicable to small size machines where economy in construction is of very great importance, 95 but it is also applicable to machines of larger size.

In accordance with the provisions of the patent statutes, I have described the principle of operation of my invention, together with the apparatus which I now consider to represent the best embodiment thereof; but 100 I desire to have it understood that the apparatus shown is merely illustrative, and that the invention can be carried out by other means.

What I claim as new and desire to secure by Letters Patent of the United States, is, 105

1. In an elastic-fluid turbine, the combination of a sup-

- 2
- port, a sheet metal bucket having a base formed integral therewith, and a device which extends across the base for securing the bucket to the support. 40
2. In an elastic-fluid turbine, the combination of a support, sheet metal buckets having a base that is common to and integral therewith, and a device which extends across the base and acts as a means common to the buckets for securing them to the support. 45
3. In an elastic-fluid turbine, the combination of a support, sheet metal buckets arranged thereon in separate rows, a base piece which is common to and integral with the buckets, and a retainer which crosses the base piece for securing the buckets and is located between the rows. 50
4. In an elastic-fluid turbine, the combination of a support, a sheet metal bucket having an integral base piece projecting each side thereof, and retainers which overlie the base piece and secure the bucket to the support. 55
5. In an elastic-fluid turbine, the combination of a support having projections thereon, sheet metal buckets which are supported by the projections, a base piece formed integral with two or more buckets which is located in the groove between the projections, and retainers that occupy the grooves and hold the buckets in place. 60
6. In an elastic-fluid turbine, the combination of a support, sheet metal buckets arranged in rows thereon, a base piece formed integral with and connecting buckets of different rows, and retainers which secure the buckets at a point between the rows. 65
7. In an elastic-fluid turbine, the combination of a support, sheet metal buckets arranged in rows thereon, a base piece formed integral with and connecting buckets of different rows, retainers which secure the buckets at a point between the rows, and means for securing the base-piece at the ends. 70
8. In an elastic-fluid turbine, the combination of a support, buckets carried thereby and arranged in rows, a base common to and integral with the buckets in different rows, and retainers for the buckets which extend across the base and are common to adjacent rows. 75
9. In an elastic-fluid turbine, the combination of a support, a plurality of buckets carried thereby and arranged in rows, the said buckets being formed of sheet metal and each provided with an integral tenon, a base piece common to and connecting buckets of different rows, and a cover that is secured to the ends of the buckets by the tenons 80
- thereon. 85
10. In an elastic-fluid turbine, the combination of a support having a deformed edge portion, with buckets having bases with outwardly projecting edges mounted on the support which are secured in place by curing the support 50 of its deformity by forcing the metal of which it is composed over one of the edges of the bucket bases to secure the buckets against movement in the plane of the support. 90
11. In an elastic-fluid turbine, the combination of a support having parallel projections thereon, with grooves between, buckets mounted on the projections having bases which extend across the grooves, and segmental locking pieces located in the grooves which extend across the bases. 95
12. In an elastic-fluid turbine, the combination of a support having parallel projections thereon, with grooves between, buckets mounted on the projections having bases which extend across the grooves, and segmental locking pieces located in the grooves which extend across the bases, and retaining devices which are common to adjacent segmental locking pieces. 100
13. As an article of manufacture, a bucket element which is punched out of sheet metal and has a base piece common to two or more buckets, the said buckets being arranged to form an angle with the base-piece. 105

In witness whereof, I have hereunto set my hand this tenth day of February, 1906.

GEORGE E. STEVENS.
